BY Thos. S. Conne.
ATTORNEY.

UNITED STATES PATENT OFFICE.

LOUIS LEWITT, OF BROOKLYN, NEW YORK.

TWO-PIECE WATCH-CASING.

1,385,839.

Specification of Letters Patent. Patented July 26, 1921.

Application filed March 5, 1921. Serial No. 449,652.

To all whom it may concern:

Be it known that I, Louis Lewitt, a citizen of the United States, residing at Brooklyn, county of Kings, and State of New York, have invented certain new and useful Improvements in Two-Piece Watch-Casing, fully described and represented in the following specification and the accompanying drawings, forming a part of the same.

This invention relates to a watch-casing intended especially for a wrist-watch but adapted for other uses; and the object of the invention is to furnish an inclosure for the movement in a very small number of pieces, and is to have the movement so sustained within the casing that the crystal shall be upon the casing body instead of upon the cover.

The cover is thus applied to the rear of the body where the regulator of the movement is located, and the mere opening of the cover thus suffices to expose the entire rear portion of the movement, thus enabling it to be inspected or the regulator adjusted.

The exposure of the works by thus opening the rear cover also affords a purchaser an opportunity of inspecting any watch offered to him for purchase, and without removing the works from the casing.

This result is attained by a particular construction, which will be understood by reference to the annexed drawing, in which Figure 1 shows the front of the watch-casing and its movement; Fig. 2 is an edge view of the same, both provided with loops for a wrist-band; Fig. 3 shows the interior of the casing-body with the cover turned at right-angles thereto; Fig. 4 is a vertical section of the casing and movement on line 4-4 in Fig. 1; Fig. 5 is an edge view of the movement detached from the casing; Fig. 6 is an edge view of the locking-ring which embraces and holds the movement in the casing; and Fig. 7 is a side view of the detachable winding-stem. The parts are greatly enlarged in the drawing to show the construction more clearly.

The casing is shown of fanciful octagonal shape, but the shape is especially adapted for manufacture from sheet-metal by drawing or stamping the parts into the desired form. The construction thus greatly cheapens the cost of the casing while affording the advantages referred to above.

The front *a* is provided with a crystal *b*

and has a flange extended straight backward from its margin forming the body *c*.

A hinge *d* connects the cover *e* with one edge of the body, and has a narrow flange *e'* at its margin which fits into a rabbet *c'* upon the rear edge of the body.

Loops *j* are shown upon the body to receive a wrist strap.

The movement *f* has a front-plate *f'* the margin of which contacts with the interior of the casing at the junction of the front *a* and body *c*, and the body is made of suitable depth to embrace substantially all of the movement.

The line of contact with the interior of the casing is suitably proportioned to make a seat to which the front plate is fitted, the body of the casing being a little larger inside than the front plate, as shown in Fig. 4, to permit the easy removal of the body from the casing when required.

The entire margin of the movement is furnished with a band *g* shown in Fig. 5, and a locking-ring *h* has a cylindrical flange *i* formed to embrace the band *g* upon the movement.

To facilitate the manufacture of the locking-ring of stamped sheet-metal, the portion *h* is formed flat and the cylindrical flange *i* projects from its inner edge, so that when fitted upon the band, the flat portion extends out to the inside of the casing as is clearly shown in Fig. 4. The cylindrical portion of the locking-ring is held upon the watch-movement by friction, and also held by friction within the rear edge of the casing-body *c*.

The margin of the flange projects around the movement and is fitted to the entire periphery of the body inside its rear edge, and necessarily corresponds in shape with the casing, whatever the design may be.

The movement is omitted from the case in Fig. 3 to clearly show the form and location of the locking-ring *h*.

The casing is made to fit the front plate *f* and margin of the movement loosely, so that when the locking-ring is removed the movement may be readily drawn out of the casing and may thus be instantly removed for examination or repairs, if desired.

A hole *k* is formed in the side of the body to insert the winding stem *l* with the crown *l'* upon the outside of the body.

With such arrangement, the stem must be

removed when the movement is to be taken from the casing, and is formed with a thread *m* upon its inner end for that purpose, as shown in Fig. 7.

5 The locking-ring is provided with a notch *n* in the lower edge of the flange *i*, to clear the winding-stem when the locking-ring is fitted within the casing.

It will be observed in Figs. 1 and 2, that 10 the opening *b'* for the crystal is in the front of the body *c*, so that the application of the cover to the rear of the body exposes the rear side of the movement when the cover *e* is opened. This arrangement affords all 15 the advantages mentioned above, of permitting a purchaser to inspect a watch movement without taking it from the casing, and permits of its regulation by the mere opening of the casing which gives full access to 20 the regulator.

It will be understood that the casing may be made of any desired shape, providing the opening for the dial is formed in the body-part of the casing as shown in the drawing, 25 and such body constructed of suitable depth to embrace the movement, and means provided in the locking-ring *h* for holding the movement in the body when the cover is opened.

30 Such locking-ring is fitted snugly to both the movement and the body, and thus operates to hold the movement in the body so long as it is embraced by the ring.

It will be observed that the entire casing 35 is formed of two pieces only, the front combined with the body-portion, and the cover which closes the rear of the case, and both parts so shaped that they can be formed by stamping from sheet-metal, thus producing 40 a very ornamental and convenient casing at the lowest possible cost.

To permit such manufacture of the casing and cover by stamping from flat sheets of metal, they are made without any under- 45 cut contour at the margin, but the body *c* projects straight backward from the front *a*, and the flange *e'* at the margin of the cover is of the same diameter as the body and projects in like manner backward from

the plane of the cover so as to fit directly 50 upon the rabbet *c'* on the rear edge of the body.

The exposure of the regulator by opening the rear cover of the casing has often been effected by making the casing of three 55 parts, to the body of which two lids were jointed to cover the front and rear parts of the movement but my invention furnishes a cheap construction for a casing having two 60 parts only.

The exposure of the regulator by opening the rear cover is secured in my construction by making the front which carries the crystal with a deep flange or body forming a box suitable to receive the entire movement, 65 in which box the movement is so inserted that the dial is exposed at the front of the casing, and the regulator is exposed merely by opening the rear cover.

Having thus set forth the nature of the 70 invention what is claimed herein is:

1. A casing for a watch-movement having a front with a crystal therein and a seat upon the inner side for the dial-plate of the movement, a body projected straight backward from the front to inclose the movement, a cover hinged to the rear of the body, and a locking-ring fitted to the rear part 75 of the movement and to the inner side of the body at its rear edge. 80

2. A casing for a watch-movement having a front with a crystal therein and a body projected straight backward from the front to inclose the movement, and a cover hinged to the rear of the body, a band embracing the margin of the movement, and a locking-ring having a cylindrical flange 85 fitted to the said band, and a flat flange projected from the rear edge of the cylindrical flange to the interior of the body at its rear 90 edge, the locking ring being fitted snugly to the said band and to the interior of the body to hold the movement in place when the cover is open. 95

In testimony whereof I have hereunto set my hand.

LOUIS LEWITT.
